UNITED STATES PATENT OFFICE.

ALBERT O. WILSON, OF WINCHESTER, MASSACHUSETTS.

STAIR.

Application filed November 5, 1926. Serial No. 146,541.

The present invention relates to stair constructions and has for its object to improve upon present-day stairs, to the end that their manufacture may be simplified and 5 their cost decreased, without in any way impairing their efficiency.

The invention will be explained in connection with the accompanying drawings, in which Fig. 1 is a vertical section through 10 a stairway constructed in accordance with the present invention, the section being taken substantially upon the line 1—1 of Fig. 4, looking in the direction of the arrows; Fig. 2 is a vertical section of a modification; Fig. 15 3 is a vertical section, upon a larger scale, taken upon the line 3—3 of Fig. 1, looking in the direction of the arrows; Fig. 4 is a similar horizontal section, taken upon the line 4—4 of Fig. 1, looking upward in the 20 direction of the arrows; Fig. 5 is a section similar to Fig. 3 of a modification; Fig. 6 is a perspective of the securing element shown in Fig. 5; Fig. 7 is a section similar to Fig. 3 of a further modification; Fig. 8 25 is a perspective of the modified securing element shown in Fig. 7; Fig. 9 is a section similar to Fig. 3 of another modification; Fig. 10 is a perspective of the modified securing element shown in Fig. 9; Fig. 11 30 is a section similar to Fig. 4 of still another modification; and Fig. 12 is a section similar to Fig. 4 of the modification shown in Fig. 9.

Three horizontal treads 2 of a stairway 35 are illustrated in Figs. 1 and 2, each connected at their ends to supports or stringers 4. These stringers are usually mounted in vertical planes, and may be constituted of standard channels, plates, bent-plate channels, and the like. Only one stringer 4 is 40 illustrated, the views being broken away so as not to show the other stringer. In Fig. 1, the treads are shown connected by risers 6. These risers may be panelled or 45 plain. In the stairs of Figs. 2, the treads are separated from each other, without any connecting risers. If risers are employed, the riser 6 of each tread may be caused to 50 lap over the tread 2 of the next higher tread, as shown at 8, and the lapped parts may be secured together in any desired way. In the case of sheet-metal risers and treads, the securing means may consist of rivets or 55 bolts 10. These rivets or bolts, together with other projecting parts 34, 38 and the like, to be described hereinafter, may

help to anchor in place a marble, slate or other stone wear plate 12, as illustrated. The lapping parts 8 of the riser 6 may aid the performance of this function. The bottom 60 of the wear plate is provided with openings to receive the projecting parts and is secured to the tread by a layer of cement or other binder that fills in the projection-receiving openings and the space above the 65 tread 2 up to the level of the lapped-over portion 8 of the riser. This provides a substantial anchoring effect to hold the wear plate in place. The separated treads shown in Fig. 2 may be made by bending a sheet 70 metal plate 14 into oblong form, with the top of the oblong open at 16. One or both sides of the sheet may terminate at 18 and 19 at the top of the oblong. Preferably, however, one of these sides is bent a small 75 distance at 20 into the top plane of the oblong and both these sides may be so bent if desired. The oblong is then filled with concrete or other filler 22. Other types of stairs, too, may equally well be employed 80 without departing from the present invention.

According to one embodiment of the invention, each tread is provided at each end with a plurality of openings (two are illustrated, but three or more may be used), shown at 24 and 26, and the stringers are each provided with a corresponding number of openings 28 and 30, the tread openings and the stringer openings being correspondingly disposed in pairs 24, 28 and 26, 30. An eyed bolt 32 extends through each stringer opening 28 and 30 and a bolt 34 extends through the eye 36 of the eyed bolt and through the opening 24 or 26, as the 95 case may be, of the tread. One or more nuts 38 serve to hold the bolt 34, the tread 2 and the eyed bolt 32 together. One or more nuts 40 threaded on the threaded end of the eyed bolt 32 holds the latter in place. 100 The tread is thus secured to the stringer by the direct interaction of the bolts 32 and 34, and rests upon the eyed bolts 32. A spacer bar or plate 42 is disposed between the tread 2 and the nuts 38, being provided 105 with openings 44 and 46 to receive the bolts 34. The spacer bar serves as a backing for the nuts 38, and also to stiffen the tread against transverse bending.

The above-described construction may, of course, be varied in many ways within the scope of the invention. Thus, instead of

using the nut 40, the free end of the eyed bolt may be bent over against, and into engagement with, the stringer, exterior to the angle between the tread and the support, as 5 illustrated at 48, Figs. 7 and 8; or the bolts 32 and 34 may be replaced by a single bent rod, as shown at 50 in these same two views and 52 in Figs. 5 and 6, the arms 53 being continuous with the rest of the rod. The 10 constructions shown in Figs. 5 to 8 are further advantageous in that they present a better appearance from below the tread, in the angle between the tread and the support, showing only the bent portion of the 15 bent rod 50 or 52. Equally efficient is the modification shown in Fig. 11, comprising a single rod having threaded arms 54 and 56 extending through the stringer openings 28 and 30, and having two bent eyes or openings 58 and 60 for alining with the tread openings 24 and 26 and the spacer bar openings and through which extend the bolts 34 to hold the parts together.

According to the modifications illustrated 25 in Figs. 9, 10 and 12, a rod 62 is provided with an end upon which the nut 40 is threaded, as in Figs. 3, 4, 5 and 11, or bent over against the stringer, as in Figs. 7 and 8, and an arm 53 continuous with the end portion, 30 as in Figs. 5 to 8. Continuous with the arm 53 is, however, a portion 64 which bends at 66 down through an additional opening 68 in the tread 2, and then backward at 70 underneath the tread. A very secure locking 35 effect is thus obtained. The openings 24 (or 26) and 68 are shown elongated in Fig. 9, to facilitate mounting the rod 62 therein. The rod 62 is first inserted through the 40 tread openings 24 and 68, then moved longitudinally through the stringer opening 28 (or 30), and the nut 40 is finally applied, locking the parts firmly together.

Other modifications, too, within the spirit 45 and scope of the invention, will readily occur to persons skilled in the art, and are intended to be expressed in the appended claims.

What is claimed is:

1. Stairs comprising a stringer, a tread 50 abutting against and extending outward at an angle from the stringer, the stringer and the tread each having a plurality of openings, the stringer openings being disposed directly adjacent to the corresponding abutting end of the tread, the stringer openings and the tread openings being correspondingly disposed in pairs, and a plurality of rods each 55 bent at an angle corresponding to the angle between the tread and the stringer, the portion of each rod on one side of the bend 60 extending from the bend in contact with the tread and through a stringer opening, and the portion of each rod on the other side of the bend extending from the bend through 65 the corresponding tread opening, the rod being unnotched at the bend so as to permit

the second-named portion thereof to extend through the said tread opening freely and so as not to weaken the rod at the bend, and means cooperating with the terminal portions of the rod that extend through the openings 70 and with the stringer and the tread, respectively, to pull the stringer and the tread tightly together, whereby the tread is tightly secured to the stringer, with the tread contacting with the first-named portion of 75 the rod, by the sole action of the rod and the said cooperating means.

2. Stairs comprising a stringer, a tread abutting against and extending perpendicularly outward from the stringer, the stringer 80 and the tread each having a plurality of openings, the stringer openings being disposed directly below the corresponding abutting end of the tread, the stringer openings and the tread openings being correspondingly disposed in pairs, and a plurality of rods each bent at substantially a right angle, the portion of each rod on one side of the bend extending from the bend below and in contact with the underside of the 85 tread and through a stringer opening, and the portion of each rod on the other side of the bend extending from the bend through the corresponding tread opening, the rod being unnotched at the bend so as to permit 90 the second-named portion thereof to extend through the said tread opening freely and so as not to weaken the rod at the bend, and means cooperating with the terminal portions of the rod that extend through the 95 openings and with the stringer and the tread, respectively, to pull the stringer and the tread tightly together, whereby the tread is tightly secured to the stringer, with the tread resting upon the first-named portion of the rod, by the sole action of the rod and the said cooperating means.

3. Stairs comprising a stringer, a tread abutting against and extending perpendicularly outward from the stringer, the stringer 100 and the tread each having a plurality of openings, the stringer openings being disposed directly below the corresponding abutting end of the tread, the stringer openings and the tread openings being correspondingly disposed in pairs, and a plurality of rods each bent at substantially a right angle, the portion of each rod on one side of the bend extending from the bend below and in contact with the underside of the 105 tread and through a stringer opening, and the portion of each rod on the other side of the bend extending from the bend through the corresponding tread opening, the rod being unnotched at the bend so as to permit 110 the second-named portion thereof to extend through the said tread opening freely and so as not to weaken the rod at the bend, and means cooperating with the terminal portions of the rod that extend through the 115 openings and with the stringer and the tread, respectively, to pull the stringer and the tread tightly together, whereby the tread is tightly secured to the stringer, with the tread resting upon the first-named portion of the rod, by the sole action of the rod and the said cooperating means.

4. Stairs comprising a stringer, a tread abutting against and extending perpendicularly outward from the stringer, the stringer 120 and the tread each having a plurality of openings, the stringer openings being disposed directly below the corresponding abutting end of the tread, the stringer openings and the tread openings being correspondingly disposed in pairs, and a plurality of rods each bent at substantially a right angle, the portion of each rod on one side of the bend extending from the bend below and in contact with the underside of the 125 tread and through a stringer opening, and the portion of each rod on the other side of the bend extending from the bend through the corresponding tread opening, the rod being unnotched at the bend so as to permit 130 the second-named portion thereof to extend through the said tread opening freely and so as not to weaken the rod at the bend, and means cooperating with the terminal portions of the rod that extend through the 135

openings and with the stringer and the tread, respectively, to pull the stringer and the tread tightly together, whereby the tread is tightly secured to the stringer, with the tread resting upon the first-named portion of the rod, by the sole action of the rod and the said cooperating means, the said means comprising a thread upon the end of the rod that extends through the tread opening and a nut threaded thereon, and a plate resting ¹⁰ upon the tread and having a plurality of openings through which the said ends of the rods respectively extend, the nuts acting to draw the first-named portion of the rod, the tread and the plate tightly together. ¹⁵

In testimony whereof, I have hereunto subscribed my name.

ALBERT O. WILSON.
